BACK SUPPORT

Clarence M. Hopper, Columbus, Ind.

Application July 15, 1947, Serial No. 760,995

1 Claim. (Cl. 155—182)

1

The invention relates to a back support, and more especially to a ventilated back-rest.

The primary object of the invention is the provision of an article of this character, wherein a person when seated in a bed, motor vehicle, house step, on a lawn or other resting locality, will be aided in comfort during sitting position, the article being thoroughly ventilated which is desirable during warm weather.

Another object of the invention is the provision of an article of this character, wherein its construction is novel and unique in entirety, it being reversible at the will of the user to assure giving comfort to the occupant and the desired support as may be required.

A further object of the invention is the provision of an article of this character, wherein it is readily portable, and is adapted for convenient service, conforming comfortably to the contour of the back of a person to give aid thereto when in a sitting position.

A still further object of the invention is the provision of an article of this character, which is simple in construction, thoroughly reliable and effective in operation, strong, durable, neat in appearance, and inexpensive to manufacture.

With these and other objects in view the invention consists in the features of construction, combination and arrangement of parts as will be hereinafter more fully described, illustrated in the accompanying drawings, which disclose the preferred embodiment of the invention, and pointed out in the claim hereunto appended.

In the accompanying drawings:

Figure 1 is a perspective view of the article constructed in accordance with the invention.

Figure 2 is a side edge view thereof.

Figure 3 is a rear elevation.

Figure 4 is a side view showing the article in one position in use.

Figure 5 is a view similar to Figure 4 showing the article in another position in use.

Similar reference characters indicate corresponding parts throughout the several views in the drawings.

Referring to the drawings in detail, the article constituting the present invention, is denoted generally at A, in its entirety, and comprises a main open-center frame 10, preferably made from bamboo or other bendable wood, metal or other suitable material, and involves longitudinal side rails 11, and opposite end rails 12 and 13, respectively, the side rails 11 being slightly converged in the direction of the end rail 13, so that the frame 10 is wider at one end than at

2

the other in the direction of the length of the same. The rails 12 and 13 are unitary continuations of the side rails 11, as should be apparent, while the end rail 12 is elbowed outwardly as at 14 in a lateral direction from the plane of side rails 11, which will be apparent from Figures 2, 3 and 4, of the drawings.

The side rails 11 and the end rails 12 and 13, respectively, have attached thereto the marginal area an open woven, bamboo or ratan braided, center covering section 15, the fastening of which is had in any desirable manner for back support in association with the frame 10 by a user.

15 Coextensive with the side rails 11 of the frame 10 and following the major length thereof are side braces 16, each straight for the greater portion of its length, which at this portion merges into the side rail next thereto adjacent to the 20 end rail 13, while the remaining portion of this brace is elbowed inwardly as at 17, and joined with the rail 11 close to the rail 12 at the elbow 14 thereof.

Crosswise between the braces 16 and spaced 25 longitudinally of the frame 10 are the rungs or brace bars or rails 18, and 19, respectively, the former being joined to the said braces 16, while the latter rung, bar or rail 19 is joined to the side rails 11 of the frame 10, the end rail 12 being outwardly arched toward the braces 16 to conform to the curvature of the back of a person, and similarly at this area the covering section 15 assumes such arched formation. The brace 18 is approximately midway of the frame 10, and the brace 19 is located near the end rail 12, as will be apparent from Figure 3 of the drawings.

The fastening of the frame and braces, as well as the covering section of the article follows the old fashioned manner of fastening cane seats and backs in the manufacture of furniture, and the overall contacting surfaces, front or back, of the article present a pleasing smoothness and attractive finish to the latter, as well as ruggedness for wear and durability.

40 The covering section 15 in its make-up assures full ventilation to the article when in use, this being clearly apparent.

The article is reversible for service, as is illustrated in Figures 4 and 5 of the drawings, and assures full comfort in either position for a back rest or support when a person is sitting.

45 The corners of the frame 10 are rounded as at 20 between the side and end rails 11, 12, and 13, thereof.

What is claimed is:

A back support of the kind described, comprising: an unbroken continuous rod-like member forming an elongated invertible frame involving opposed longitudinal side and transverse end rails, respectively, the side rails being converged in the direction of one end rail for varying the width of said frame from end to end, a reticulated center section bounded by and joining the frame, side braces connected to the side rails intermediate of the ends of the frame and having elbows connected to the side rails at the wider end of said frame for disposing the braces at an angle to the latter, elbows formed in the

frame at its wider end to offset a part of the center section correspondingly to the plane of said braces, and spaced cross-rungs on the frame and braces, respectively.

CLARENCE M. HOPPER.
